UNITED STATES PATENT OFFICE.

JOSEPH HIRAM LOWE, OF ST. JEROME, QUEBEC, CANADA.

MECHANICAL STOKER FOR LOCOMOTIVE-BOILERS.

No. 924,364.

Specification of Letters Patent.

Patented June 8, 1909.

Application filed July 10, 1908. Serial No. 442,988.

To all whom it may concern:

Be it known that I, JOSEPH HIRAM LOWE, of St. Jerome, in the Province of Quebec, Dominion of Canada, have invented certain new and useful Improvements in Mechanical Stokers for Locomotive-Boilers, of which the following is a specification.

My invention relates to improvements in mechanical stokers for locomotive boilers and the objects of my invention are to provide a simple and efficient device of this class which may be easily and readily disconnected to permit of ordinary hand firing; and it consists essentially of the improved construction hereinafter more fully set forth and described in the accompanying specification and drawings.

In the drawings, Figure 1 is a side view partially in section of the rear cabin of a locomotive and tender equipped with my stoker. Fig. 2 is a top plan view also partially in section. Fig. 3 is an enlarged detail with the firing door open. Fig. 4 is an enlarged perspective detail through the connection between the fuel bin and the conveyer on the line 2—2, Fig. 1. Fig. 5 is a bottom view of the connecting member between the fuel bin and the conveyer.

In the drawings like characters of reference 30 indicate corresponding parts in each figure.

A represents the cabin of the locomotive and B the tender thereof. C represents the fire box and D the hopper-shaped door thereof. In accordance with 35 my invention, this door is made in the form of a hollow shell and has at the top thereof a chute a which is connected to a conveyer tube E which has an aperture b immediately above the chute. In order to permit the free 40 opening of the door it is necessary to make this connection of a swiveling character and while a variety of different swivels may be employed, the one I have illustrated consists of a rod c connected to the door, having an 45 eyelet d on the top thereof, through which a rod e connected to the conveyer tube extends, the said rod having a plurality of notches f therein, by means of which the door may be held in a partially open position. I 50 also form a flange g around the aperture b in order to better direct the continuous discharge out of the same. When the door is swung open, the eyelet d will slide along the rod e and may be held in engagement 55 with any of the notches f according to how far it is desired to swing the door open. The

end of the tube E will thus be supported by the rod c as shown clearly in Fig. 3.

Within the door D are a plurality of discharging plates h secured to a transverse shaft i which is connected by a suitable coupling j with a shaft k journaled on the sides of the boiler head, and suitably connected to a prime motor F which may be operated by steam, gas, electricity or other 65 source of power.

Beneath the distributing arms and pivoted to the lower edge of the door is a spreader G, adapted, when the door is closed, to remain in substantially horizontal position, and 70 having the inner end l bifurcated and upturned, whereby the fuel thrown by the distributing plate will be evenly spread. This spreader has a weighted arm m extending outwardly therefrom, which is adapted to 75 swing it into a vertical position when the door opens. To bring it again into a horizontal position on the closing of the door a projection n is provided adapted to engage the edge 80 of the opening in the boiler head.

The coupling j herein mentioned, will be of any simple type which may be quickly and easily disconnected and connected and its construction being well known in the art need not be herein further described.

Within the conveyer tube E is located a spiral conveyer H, supported on a shaft 15, the one end of which has a sprocket q thereon connected by a chain r or other gearing with a pulley on the axle of one of the pair of car-wheels. This pulley will be thrown in and out of gear with the axle by means of a suitable clutch (not shown), the said clutch being operated by a chain t connected by a rod u operable from the front of the tender. 95

The inner end of the conveyer tube has a swiveling connection with the tender, that shown comprising a lug v connected to the conveyer tube, which is pivoted to a rod w supported from the bottom of the tender 100 with freedom to rotate. Through the upper side of the conveyer tube and within the fuel bin I an aperture x is provided for the entrance of fuel, the said aperture being opened and closed by a tube J extending about the 105 conveyer tube and having an aperture y therein corresponding to the aperture x. This outer tube J has connected thereto external to the tender, a hand lever z by means of which it might be rotated. The tube J 110 will also have a transverse slot therein, through which the lug v will extend, the said

slot being sufficient to permit of the free rotation of the tube.

Owing to the jolting of the tender, it is necessary to have a more or less flexible connection between the conveyer tube and the fuel bin, and this I form by means of a connecting member K consisting of a rectangular frame, having sides L-shaped in cross-section, the sides being adapted to fit exactly within a chute L supported separate from the conveyer tube and emptying into the aperture thereof, the tube J however, extending between the bottom of the chute and the conveyer tube. The conveyer E is preferably connected to one side of the center of the fuel bin whereby the other side will be free and clear for hand firing. The top face of the frame is adapted to abut the underside of the bottom of the fuel bin, which has an aperture 6 adapted to empty into the chute. To retain the connecting member in position, projections 7, 8 and 9 are provided, which engage plates or flanges 10, 11 and 12 respectively, secured to the bottom of the fuel bin.

In operation, when the door is closed, and the ports are in the relative position shown in Fig. 1, the spiral conveyer is continuously rotated through the medium of the prime motor, and this causes the fuel to be carried from the coal bin and emptied into the chute a, whence it passes into the hopper-shaped door D, and is distributed by the rotating arm h, the spreader G operating to evenly spread the fuel on the fire bed. Should the apparatus clog, or should it be desirable at any time, to resort to hand firing, the shaft k may be rotated to a determined position and the fire door swung open for hand firing. It will thus be seen that I have devised an exceedingly cheap and simple form of mechanical stoker for locomotives, which will operate to continuously fire the same, but which will not interfere with hand firing, if this be desirable.

A device of this character is exceedingly important, owing to the increasing size of locomotives, which renders it impossible for a single fireman to properly fire.

While the invention has been described herein with great particularity of detail, it will be readily understood that in carrying out the construction of the same, changes, within the scope of the appended claims, may be made therein, without departing from the spirit of the invention.

What I claim as my invention is:—

1. In a mechanical stoker for locomotive boilers and in combination, a fire box having a suitable opening thereon, a hinged hopper adapted to close the opening and discharge

into the fire box, a conveyer connected to the hopper and discharging into the same, means for placing the opposite end of the conveyer in communication with a supply of fuel, means for operating the conveyer, a fixed spreading device hinged to the bottom of the hopper, a weighted arm thereon adapted to bring the same into vertical position when the hopper is open, a projection on the spreading member adapted to engage the edge of the opening of the fire box to hold the spreading member in substantially horizontal position when the hopper is closed, rotatable distributing arms supported in the hopper and adapted to co-act with the spreading members and means for rotating said arms.

2. In a mechanical stoker for locomotive boilers, and in combination, a fire box having an opening therein, a hinged hopper closing the opening, a tender, a fuel bin therein, a conveyer discharging into the hopper and extending below the fuel bin, and a connecting member slidably engaging the bottom of the fuel bin, and having loose engagement with the conveyer whereby slight relative movement will be permitted between the end of the conveyer and the connecting member.

3. In a mechanical stoker for locomotive boilers, the combination of a fire box having an opening therein, a hinged hopper closing the opening, and discharging into the fire box, a fuel bin, a conveyer tube discharging into the hopper and extending toward the fuel bin, a conveyer in the conveyer tube, and means for operating the same, a chute discharging into the inner end of the conveyer, a loose connecting member including a frame formed with projections thereon and having the upper surface in contact with the bottom of the fuel bin and having the sides engaging the top of the chute, and flanges on the fuel bin engaging the projections on the connecting member.

4. In a mechanical stoker for locomotive boilers, the combination of a fire box having an opening therein, a hinged hopper closing the opening and adapted to discharge into the fire box and having an aperture therein, a conveyer tube adapted to discharge into the aperture, a rod connected to the hopper having an eyelet therein, a rod connected to the conveyer tube extending through the eyelet and having a plurality of notches formed thereon.

In witness whereof I have hereunto set my hand in the presence of two witnesses.

JOSEPH HIRAM LOWE.
